UNITED STATES PATENT OFFICE.

ROBERT R. WEAVER, OF COLUMBUS, OHIO, ASSIGNOR TO THE RALSTON STEEL CAR COMPANY, OF COLUMBUS, OHIO.

DROP-DOOR-OPERATING MECHANISM FOR DUMPING-CARS.

1,124,188.

Specification of Letters Patent.

Patented Jan. 5, 1915.

Application filed September 11, 1914. Serial No. 861,228.

To all whom it may concern:

Be it known that I, ROBERT R. WEAVER, of Columbus, in the county of Franklin and State of Ohio, have invented certain new and useful Improvements in Drop-Door-Operating Mechanism for Dumping-Cars; and I do hereby declare the following to be a full, clear, and exact description of the invention, such as will enable others skilled 10 in the art to which it appertains to make and use the same.

My invention relates to improvements in drop door operating mechanism for dumping cars and more particularly to hopper bottom cars such as are employed for carrying ore, etc.

One object of the invention is to so construct a hopper bottom car and door operating mechanism therefor, that a maximum 20 opening shall be afforded when the doors are dropped by said mechanism.

A further object is to so construct door operating mechanism that the doors may be opened in such manner as to prevent arching 25 of the material over the door opening.

A further object is to so construct and arrange drop door operating mechanism that it shall be disposed in such manner as to operate at right angles to the line of motion 30 of the car, and thus reduce liability of being accidentally released by the longitudinal shocks incident to the sudden starting or stopping of the car.

A further object is to construct drop door 35 operating mechanism in such manner, that said mechanism shall be relieved from excessive strain and shock when the doors are dropped and forced open violently by descent of the load.

A further object is to provide simple and 40 efficient lock-operating means for drop door operating mechanism.

With these and other objects in view, the 45 invention consists in certain novel features of construction and combinations of parts as hereinafter set forth and pointed out in the claims.

In the accompanying drawings; Figure 1 is a plan view illustrating the application 50 of my improvements to a hopper bottom car; Fig. 2 is a side view; Fig. 3 is a transverse sectional view on a larger scale; Fig. 4 is a partial sectional view at right angles to Fig. 3, and Figs. 5, 6 and 7 are detail 55 views.

1 represents a hopper bottom car such as employed for transporting ore, coal, etc., and 2, 2 indicate the draft beams of the car. The lower portion of the hopper body of the car is located between the inner ends of the draft beams at respective ends of the car, and the pairs of draft beams are rigidly connected with the hopper body. The opening 3 in the bottom of the hopper body 1 is of considerable size, both in longitudinal and transverse dimensions, and is closed by two drop doors 4, 4. The doors are hinged at respective sides of the door opening 3 somewhat inwardly of the line of the car wheels 5, so that when said doors are open (as indicated by dotted lines in Fig. 3) they will be vertically disposed inside of the lines of the car wheels and of the track rails. Each door is provided on its bottom with an inclined brace 6 spaced from the free edge of the door by a suitable T or angle bar 7,—said braces also serving as trackways for parts of the operating mechanism as hereinafter explained. The operating mechanisms for the doors are supported, for the most part, from the draft beams and between the same in proximity to the ends of the hopper body, and said operating mechanism is duplicated at respective ends of the body 1, except as hereinafter specifically pointed out. Links 8, 8, are suspended from brackets 9^a secured to the draft beams at respective ends of the lever portion of the body 1, and the links at one end of the hopper bottom are connected with those at the other end, by rods or bars 9 disposed under the doors, and on these rods or bars, rollers 10 are mounted so as to run against the braces or trackways 6 on the doors, and the latter are provided with stops 11 to receive 95 said rollers or the rods or bars on which they are mounted, when the doors are dropped, so as to prevent said doors from swinging far enough laterally to discharge portions of the contents of the car over the 100 track rails.

Referring now more particularly to Figs. 3, 4 and 7 of the drawing, which shows the door operating mechanism at one end of the bottom of the hopper body, 12, 13 represent 105 alining shaft sections mounted in suitable bearings 14, 15, below and centrally between the planes of the draft beams. A cross head 17 is secured to the shaft section 12, and to its right hand end, as 110

viewed in Fig. 3 of the drawing, one end of a curved link 18 is pivotally attached, the other end of said curved link being pivotally connected at 19 with the left-hand depending link 8. A curved link 20 is pivoted at one end to the left hand end of the cross-head 17 and at the other end to the right-hand depending link. When these parts are in their normal positions and the doors closed, the pivotal connection of the curved link 18 with the left-hand depending link 8 will be disposed slightly below the center line of the shaft and cross head, so that the load on the doors will not force them open until the cross head shall have been turned sufficiently to overcome the dead centers of the link connections. The shaft sections 12-13 are connected by a clutch device capable of relative movement approximately equal to the extent of turning movement of the shaft section 12, for a purpose which will be hereinafter explained. In constructing the clutch devices above referred to, the shaft section 12 is provided with a clutch member 21 having a lug 24, and the shaft section 13 has secured thereto, a recessed clutch member 23 to receive the clutch member 21. The clutch member 23 is provided with a lug 22 to coöperate with the lug 24 on the clutch member 21 and the lugs on the two clutch members are so proportioned as to admit of the relative movements of the shaft sections hereinbefore referred to. The clutch member 23 (at one end of the car body) is provided with peripheral teeth, whereby a ratchet wheel 25 is formed, but at both ends of the car body, the clutch member 23 is provided with teeth to form a gear wheel 26, the ratchet wheel 25 and its coöoperating devices being provided only at one end of the car body.

Disposed between the draft beams 2 (at each end of the body 1) and having its axis parallel with said beam, is a gear 27 which, as shown in the drawing, may comprise two oppositely disposed toothed segments 28-29,--the former of which meshes with the gear or pinion 26. The segment 29 meshes with and receives motion from a rack bar 30 (preferably formed of channel iron) which passes transversely through suitable openings in the webs of the draft beams. The rack bar 30 is of sufficient length to extend approximately to the sides of the car and terminate under the side sills. Shafts 31 are mounted in suitable bearings near the sides of the car, preferably under the side sills, and parallel with the latter, and these shafts carry pinions 32 to mesh with the end portions of the transverse rack bars at respective ends of the car body 1. The shafts 31 are adapted at their ends to receive a suitable arm or lever for manually operating them. Guide rollers 33 may be provided for the rack bars

and mounted in suitable bearings above the pinions 32 and segments 29.

In order to insure the secure locking of the door operating mechanism and of the doors when the latter are closed, a pivoted pawl 34 is provided and so located as to engage the ratchet wheel 25. This pawl is held normally locked by means of a pivoted dog 35, and said pawl and dog are loosely connected together by means of a link 36 pivoted to the pawl 34 and engaging an elongated slot 38 in the dog 35. A rod or shaft 39 is mounted transversely of the car at one end of the body 1, and is provided at respective ends near the sides of the car, with handles 40. At a point between the draft beams, the rod or shaft 39 is provided with a crank arm 41 which is connected, by means of a rod 42 with the locking dog 35.

It will be observed that the operating mechanism for the drop doors is disposed transversely of the car and thus the sudden stopping or starting of the car is not liable to release or operate said mechanism, as might occur with mechanism arranged to move in directions parallel with the direction of motion of the car. It will also be noticed that my improved door operating mechanism is operable from the sides of the car and the necessity for entering between the cars to release or restore the drop doors is obviated, and furthermore the construction and arrangement of my improvements are such that there will be no liability of the material in the car arching over the outlet when the doors are opened.

In operating the mechanism to discharge the contents of the car, the trainman will first turn the rod or shaft 39 to release the dog 35 from the pawl 34 and to raise the latter from engagement with the ratchet wheel 25. He will then turn one of the shafts 31 to impart motion to the rack bars 30. Motion thus imparted to the rack bars 30 will be transmitted to the segmental gear 27 and by the latter to the pinions 26 on shaft sections 13. The motion thus imparted to the shaft sections 13 will be imparted, through the medium of the clutch devices 22-23 to the shaft sections 12. As soon as the shaft sections 12 shall have been turned to overcome the dead centers of the link mechanism which connects said shaft sections 12 with the doors, the weight of the ore or other material will force said doors fully open. During the opening movement of the doors, each shaft section 12 will turn so that the lug on the clutch member 21 will move from one end to the other of the lug in the clutch member 23, and thus the door operating gearing will be relieved of all strain and shock incident to the violent opening of the doors. To effect the closing of the doors, the train-

- man will turn one of the shafts 31 in the reverse direction and thus impart motion through the rack bars 30 gears 27 and pinions 26 for rotating the shaft sections 13.
- 5 The lug of the clutch member 23 on shaft section 13, now in engagement with the lug of clutch member 21, will cause the shaft section 12 to turn and impart motion, through the medium of the link mechanism 10 to swing the doors to closed position. The rod or shaft 39 may now be operated to permit the pawl 34 and dog to assume their locked position to lock the door-operating mechanism with the doors closed.
- 15 Various changes might be made in the details of construction of my invention without departing from the spirit thereof or limiting its scope and hence I do not wish to restrict myself to the precise details here- 20 in set forth.

Having fully described my invention what I claim as new and desire to secure by Letters-Patent, is:—

1. In a dumping car, the combination with 25 a hopper body and drop doors therefor, of link mechanism coöperative with said doors, gearing disposed parallel with the longitudinal axis of the car for operating said link mechanism, a transversely disposed rack bar 30 for operating said gearing, and means at the sides of the car for operating said rack bar.
2. In a dumping car, the combination with 35 a body and drop doors therefor, of link mechanism for operating the doors, gearing for operating said link mechanism, a trans- 40 verse rack bar for imparting motion to said gearing, and means at the sides of the car for operating said rack bar.
3. In a dumping car, the combination with 45 a body and drop doors therefor, of link mechanism for operating the doors, gearing for operating said link mechanism, a trans- 50 versely disposed rack bar for operating said gearing, a manually operable shaft near the side of the car, and a pinion carried by said shaft and meshing with said rack bar.
4. In a dumping car, the combination with 55 a body and drop doors, of suspended links near opposite ends of the open bottom of 50 the car body, door engaging rods carried by said links, cross-heads disposed between the

pairs of suspended links, a link connecting one end of a cross head with the suspended link farthest therefrom, a link connecting the other end of said cross-head with the 55 other suspended link, the pivotal connections between said links and cross heads being such that the doors will be held normally closed, and means for turning the cross head to overcome dead centers in the 60 link connections to release the doors.

5. In a dumping car, the combination with 65 a body and drop doors therefor, of pairs of suspended links, door engaging rods carried by said links, a cross head mounted between each pair of suspended links, a curved link connected at one end to one end of the cross head and at the other end to the farthest removed suspended link, a link connecting the other end of the cross head with the 70 other suspended link of the pair, mechanism disposed transversely of the car for operating said cross head, and means at the side of the car for operating said transversely disposed mechanism. 75

6. In a dumping car, the combination with 80 a car body and drop doors, and link mechanism for operating said doors, of a gear connected with said link mechanism, a transversely disposed rack bar, a gear interposed between said rack bar and the first mentioned gear and means at the sides of the car for operating said transversely disposed rack bar.

7. In a dumping car, the combination with 85 a body, drop doors therefor, operating mechanism for said drop doors, and a ratchet wheel carried by said door operating mechanism, a pivoted pawl to engage said ratchet wheel, a pivoted dog to lock said 90 pawl, a loose link connecting said pawl and dog, a transverse rod operable from the side of the car and having a crank arm, and a rod connecting said crank arm with the pivoted dog. 95

In testimony whereof, I have signed this specification in the presence of two subscribing witnesses.—

ROBERT R. WEAVER.
